UNITED STATES PATENT OFFICE.

LOUIS STEIN, OF CHICAGO, ILLINOIS.

INDEX TAB.

Application filed December 7, 1922. Serial No. 605,364.

To all whom it may concern:

Be it known that I, LOUIS STEIN, a citizen of the United States, residing at Chicago, in the county of Cook and State of Illinois, 5 have invented a certain new and useful Index Tab, of which the following is a specification.

The invention relates to the art of manufacturing tabs for use in supporting index 10 cards upon filing folders and the like.

The object of the invention is to provide a tab of extremely simple construction capable of manufacture at a relatively small cost and yet serving to accomplish effectually 15 the purpose for which it is intended.

More specifically stated, the aim is to provide an index tab formed primarily from sheet celluloid, the invention relating more especially to an improved and simplified 20 method of fastening the tab in place upon the edge of a sheet.

In the accompanying drawings I have shown for purposes of illustration two forms of my invention. Figure 1 is a front 25 elevational view of a filing folder of the type generally known as a desk organizer, and equipped with one form of index tab. Fig. 2 is a fragmentary detail perspective view of this form of tab. Fig. 3 is a fragmentary perspective view of the parts at 30 one stage of the manufacturing operation. Fig. 4 is a side elevational view of a filing folder having leaves of the same width and provided with index tabs arranged in offset 35 relation. Fig. 5 is a fragmentary sectional view taken in the plane of line 5—5 of Fig. 1. Fig. 6 is a similar view but showing the tab before it is applied to the edge of the sheet.

40 My improved tab is made from a piece of transparent celluloid provided with a backing of suitable material and gummed to enable it to be readily secured to the edge of a leaf of a filing folder or the like. The 45 form of the tab shown in Figs. 1 to 3, wherein the tab is secured to the free edge of the leaf or sheet but does not project therefrom, comprises a piece of celluloid 7 substantially 50 rectangular in form mounted upon a backing 8. The latter is of similar shape, made of cloth or other suitable material, and has a gummed outer face 8^a. The celluloid and its backing are secured together along opposed marginal edges preferably by means 55 of stitching 9.

It will be apparent that the tabs may be

secured in place upon the free edges of the leaves 10 of a filing folder simply by moistening the gummed surface of the cloth backing and doubling the tab from 60 its flat form, approximately on a line midway between the stitched edges thereof, over and upon the opposite surfaces of the leaf or sheet 10 near the free edge thereof, as shown clearly in Fig. 2. When the tab 65 is thus secured in place, index cards 11 are inserted between the celluloid and the backing, and it will be apparent that inasmuch as the side edges of the latter adhere closely to the surfaces of the sheet 10, whereas the 70 edges of the celluloid are free to bulge upwardly away from the sheet, the operation of inserting the card is greatly facilitated. As shown in Fig. 5 the index tab thus provided serves to retain cards on both sides of 75 the leaf or sheet 10.

In the manufacture of the tabs, the celluloid and the cloth backing are cut into relatively narrow strip form, and the separate strips are then placed in proper face to 80 face relation and secured together along their longitudinal edges. Indeed, the tabs may, if desired, be sold in strip form, in which event the tabs would be severed from the strip when needed. A portion of a completed strip is shown in Fig. 3.

In case the tabs are to project beyond the edge of the sheet of the filing folder, a narrow strip of paper or thin cardboard 13 (Fig. 6) is inserted within the fold of the 90 tab in place of the edge of the sheet 10. This strip serves simply to provide a means to which the gummed backing may be secured, leaving the side edges of the celluloid to bulge upwardly, as shown in said 95 figure, to facilitate the insertion of the cards. It will also be seen that this strip is made somewhat narrower than the cloth of the folded tab, thus leaving projecting edge portions 14, gummed upon their inner sides, 100 for securing the tab upon opposite side faces of the sheet 10.

It will be observed that the index tab which I have thus provided is capable of manufacture on a very economical basis; can 105 be quickly and easily attached to the filing folder or other article; and by reason of the ease with which they may be secured in position it is possible to secure their proper alinement upon the several leaves of the 110 folder without the exercise of undue precaution.

I claim as my invention:

1. An index tab formed from a sheet of celluloid, a backing sheet of substantially the same size as the celluloid sheet and secured thereto along parallel edges by stitching, said sheets being bent upon themselves substantially midway between their fastened edges and the backing being provided with a gummed surface to enable it to be secured to the leaf or sheet of a filing folder or the like, and a strip of material inserted between the folded sheet of backing and secured thereto by the adhesive of the backing, said strip being somewhat narrower than the depth of the fold so as to leave projecting portions of the backing with gummed surfaces for securing the tab to the edge of a filing folder or the like.
- 10 2. An index tab formed from a sheet of celluloid, a backing for said sheet secured
- 15 tabs on one or both sides of the leaf to which the tab is attached.

thereto along parallel edges, said sheets being bent upon themselves substantially midway between their fastened edges and the backing being provided with a gummed surface to enable it to be secured to the leaf or sheet of a filing folder or the like, and a strip of material inserted between the folded sheet of backing and secured thereto by the adhesive of the backing, said strip being somewhat narrower than the depth of the fold so as to leave projecting portions of the backing with gummed surfaces for securing the tab to the edge of a filing folder or the like.

In testimony whereof, I have hereunto affixed my signature.

LOUIS STEIN.
